UNITED STATES PATENT OFFICE.

SALISBURY M. DAY, OF ROCHESTER, NEW YORK, ASSIGNOR TO GENERAL RAILWAY SIGNAL COMPANY, OF GATES, NEW YORK, A CORPORATION OF NEW YORK.

LAMP ADAPTER.

Application filed April 18, 1922. Serial No. 555,345.

To all whom it may concern:

Be it known that I, SALISBURY M. DAY, a citizen of the United States of America, residing at Rochester, in the county of Monroe and State of New York, have invented certain new and useful Improvements in Lamp Adapters, of which the following is a specification.

This invention relates to adapters, and particularly to adapters for positioning an incandescent lamp filament with respect to the lens of a light signal.

The employment of concentrated filament lamps of the incandescent type for light signaling purposes, requires such concentrated filament to be located substantially at the focus of the lens in order to properly concentrate and direct the light. Lamps of this kind manufactured in quantity and on a commercial scale do not have their filaments definitely located with respect to the lamp bases, due to inaccuracy of manufacture. In order to properly locate a filament with respect to a lens without making adjustments at the time the lamp is installed in the signal casing, it has been proposed to provide adapters which may be clamped between the signal casing and the lens thereof, which may be provided with a concentrated filament lamp properly adjusted with respect to the adapter, and consequently with respect to the lens some time before it is to be used, that is, to provide such adapters with lamps therein for reserve purposes.

It has been found very tedious and almost impossible for one workman to install such an adapter on account of the many parts to be handled, such as, adapter, lens, bezel ring, gasket, bolts, and the like.

With the above and other considerations in mind, the principal objects and purposes of the present invention contemplate the provision of an adapter for such light signals which may be clamped on the lens, thereby providing a unitary structure which may be easily installed, and which includes suitable means for adjusting the filament of an incandescent lamp with respect to such adapter and lens. Other objects and advantages of the present invention will appear as the description thereof progresses.

In describing the invention in detail, reference will be made to the accompanying drawing, in which:—

Fig. 1 shows a cross-sectional view of a

typical light signal casing, having an adapter embodying the present invention applied thereto;

Fig. 2 illustrates an end view of a light unit, comprising a lens and adapter provided with a lamp; and

Fig. 3 is a side elevation of the device shown in Fig. 2, portions thereof being shown in section for clearness.

In describing the invention in detail, attention is first directed more particularly to Fig. 1, which illustrates a typical light signal casing used for railway signaling purposes. This signal casing comprises a casing 1 of general box-like shape provided with a cover 2 terminating in the form of a hook 3 adapted to hook over the front wall of the casing 1, and held in place at the other extreme end of the casing by a hasp fastener 4, this cover 2 being provided with a handle 5 to facilitate its removal.

The front wall of the casing 1 is provided with a large circular opening, which is provided with an internal flange 6, thereby providing a seat for supporting a lens 7. This lens is supported in the usual manner between the gaskets 8 and 9 by a bezel ring 10 fastened to the casing by bolts 11. If the adapter embodying the present invention is used in connection with this lamp casing, an additional or spacing gasket 12 is inserted between the front wall of the casing 1 and the bezel ring 10.

This adapter, more clearly illustrated in Figs. 2 and 3, comprises a tripod, so to speak, consisting of a base member 13 comprising a casting of general ring-like shape having an extension 14, and provided with three extending spring arms 15. These arms are bent to diverge at their free ends and terminate in substantially parallel extensions 16, to embrace the outside edge of the lens 7. Although these arms are constructed of spring material they are rather stiff, so that the base of the adapter carrying the incandescent lamp 17 will be firmly supported when the adapter and lens are held in place by the bezel ring. Near the free end of each of the arms is provided a spring-clip 18 of general U-shape. This spring-clip is bent to form hooks adapted to engage the outside face of the rim of the lens 7.

The extension 14 is provided with a saw-slot 19, as indicated, and is bored in a direc-

tion parallel to the saw-slot 19 in a manner to provide a spherical hollow which is adapted to receive a split-sleeve 20 having a spherical external surface. In this split-sleeve 5 is slidably supported a lamp socket 21 of the well-known bayonet type having a general cylindrical external surface, which is adapted to receive an incandescent lamp of the concentrated filament type. This socket 10 21, as is obvious from the drawing, may be adjusted slidably and pivotally with respect to the ball and socket joint formed by the extension 14 and the sleeve 20. After such adjustment, the socket 21 may be firmly 15 clamped in place by tightening the lock screw 27.

The incandescent lamp 17 shown is provided with two filaments 22 and 23 which are connected in multiple, so that they are 20 both illuminated when intact. If one or the other of the filaments burns out, signaling therewith is still possible, but the weakness of the light source serves as an indication that only one filament is intact, and 25 that the lamp should be renewed.

A terminal board 24 is screw fastened against the extension 14 by a screw 25. This terminal board is provided with binding posts 26 permanently in electrical contact 30 with the contacts of the sockets 21, which facilitate ready connection of the supply wires (not shown) to the adapter.

In practicing the present invention, it may be assumed that a large number of signal installations have been made, each of 35 which consists of a suitable lamp casing having a light unit of the type just described. A large number of adapters are preferably kept in stock, or in reserve, having a concentrated filament lamp, preferably of the 40 two-filament type, located at the focal point of a lens of the kind used in such installations. If now one of the filaments of any one of the light signals burns out, the particular signal will still be effective, but it may 45 be readily observed that only one filament is intact, and that the lamp should therefore be replaced.

In replacing such a lamp the lens, adapter 50 and burnt out lamp are all removed together, the lens is then removed from the adapter, and this lens is placed into a different adapter having a new lamp which has had its filament previously adjusted with 55 respect to a lens of the same focal dimensions. This adjustment of the filament with respect to the lens may be accomplished in any suitable manner, but is preferably done by placing the adapter in a suitable jig provided with suitable sighting devices, where- 60 by the relative position of the filament and the adapter may be observed. This new light unit comprising the same lens and a

different adapter provided with a new lamp is then placed in the lens opening of the 65 light signal casing, and is clamped in place by the bezel ring 10 in the usual manner.

It should be especially noted that the unitary construction afforded by an adapter of this kind, permits the assembling of an 70 adapter and lens by reaching into the casing with one hand to support this unit, thereby leaving the other hand entirely free for fastening the bezel ring in place. If extreme accuracy in focusing the filament of a signal 75 of this kind is required, the reserve units may also include the lens with which the adapter is to be used. In this event the entire light unit comprising a lens, adapter and incandescent lamp is interchanged at 80 each replacement of a burnt out lamp.

It should be noted that since this adapter is supported directly from the lens of a light signal, it may be applied to a signal 85 which was originally constructed and installed as an oil lamp signal, by applying the adapter directly to the lens of such signal, a spacing gasket, such as the gasket 12, being possibly necessary to afford room for 90 the free ends and hooks of the arms 15.

Having thus shown and described one specific embodiment of my invention, I desire to have it understood that this does not exhaust the idea of means of carrying out this invention, but merely illustrates its nature 95 and mode of operation.

What I desire to secure by Letters Patent, is:—

1. An adapter for supporting incandescent lamps of commercial manufacture in 100 light signals so that the filament of the lamp has the proper relation to the lens of the signal comprising, a base member, a lamp socket adjustably fastened to said base member, three relatively stiff arms extending 105 from said base member having their free ends shaped to engage the outer edge and the inside face of a lens, and relatively thin spring strips fastened to said arms and shaped to engage the outside face of said 110 lens.

2. An adapter for supporting electric lamps comprising, a base member, a lamp socket supported by said base member, spring arms extending from said base member and having their ends shaped to embrace the outer edge and the inside face of a lens in different radial planes, and a hook shaped spring clip secured to the free end of each 115 of said arms and shaped to engage the front 120 face of said lens in a different radial plane than does the arm to which it is secured.

In testimony whereof I hereby affix my signature.

SALISBURY M. DAY.
